UNITED STATES PATENT OFFICE.

THOMAS H. BICKERTON, OF LIVERPOOL, ENGLAND.

DESIGN FOR A RETINOSCOPE MEMBER.

SPECIFICATION forming part of Design No. 35,469, dated December 24, 1901.

Application filed January 2, 1900. Serial No. 170. Term of patent 7 years.

To all whom it may concern:

Be it known that I, THOMAS H. BICKERTON, a subject of the King of Great Britain, and a resident of Liverpool, in the county of Lancaster, England, have invented and produced a new and original Design for a Retinoscope Member, of which the following is a specification, reference being had to the accompanying drawings, in which—

Figure 1 is a perspective view of one member of a retinoscope. Fig. 2 is a bottom plan view of the member.

As shown in the drawings, the leading or material features of my design consist in the shape of the member, comprising a disk-like part 1, milled on its edge, having a central concave depression 2 on its upper face, in the center of which is an aperture 3, extending

entirely through the member. A flat annular lug extends laterally from the edge at one side of the upper face of the member, from which a post 5 depends. The other or bottom face of the member has an annular rim or bead 6 entirely surrounding it.

Having thus described my invention, the following is what I claim as new therein and desire to secure by Letters Patent:

The design for a retinoscope member as herein shown and described.

In witness whereof I have hereunto signed my name, this 13th day of December, 1890, in the presence of two subscribing witnesses.

THOMAS H. BICKERTON.
